ANKLE SPLINT

Fred R. Dunning and Jean R. Dunning, both of
3800 Oakes Road, Brecksville, Ohio 44141

Filed Mar. 19, 1969, Ser. No. 16,320

Term of patent 14 years

Int. Cl. D24—05

U.S. Cl. D83—1

Fig. 1

Fig. 2

Fig. 3

FIG. 1 is a top plan view of the ankle splint embodying our new design;

FIG. 2 is a bottom plan view thereof;

FIG. 3 is a side elevational view;

FIG. 4 is a right side view of the ankle splint shown placed in position on the ankle of a patient;

FIG. 5 is a front elevation of the ankle splint placed on the ankle of the patient;

FIG. 6 is a rear elevation of the ankle splint; and

FIG. 7 is a left side view.

The broken lines representing a patient's ankle are shown for illustrative purposes only and do not form part of the claimed design.

We claim:

The ornamental design for an ankle splint, substantially as shown and described.
